UNITED STATES PATENT OFFICE.

WILLIAM JAMES MORTON, OF NEW YORK, N. Y.

RAILWAY-TIE.

1,097,253.

Specification of Letters Patent.

Patented May 19, 1914.

Application filed March 11, 1911. Serial No. 213,755.

To all whom it may concern:

Be it known that I, WILLIAM JAMES MORTON, a citizen of the United States, a resident of the borough of Manhattan, city, 5 county, and State of New York, have invented a new and useful Railway-Tie, of which the following is a specification.

The object I have in view is the production of a railway tie, which will have the 10 elasticity of the established wooden tie, together with the easy means of attachment of the rail thereto, and which will also have the durability, strength and extent of bearing surface of a concrete tie.

15 Further objects of the invention will more fully appear from the following specification and accompanying drawing, considered together or separately.

In the drawing: Figure 1 is a plan view 20 of a railway tie, showing one embodiment of my invention. Fig. 2 is a section on the line 2—2 of Fig. 1. Fig. 3 is a section on the line 3—3 of Fig. 2. Fig. 4 is a section on the line 4—4 of Fig. 2. Fig. 5 is a longitudinal section of a mold in which the tie 25 may be formed, showing the core blocks and with the reinforcements in place. Fig. 6 is a plan view of a modified form of tie embodying my invention. Fig. 7 is a section on 30 the line 7—7 of Fig. 6; and Fig. 8 is a section of a modified form of tie, similar to the section of which Fig. 3 is a view, the difference between this modification and that of the preferred embodiment of my invention lying in the position of the rods and 35 the shape of the blocks.

According to my invention, the tie essentially comprises a concrete portion 1, and blocks 2, 2. These blocks are preferably 40 shorter than the tie, and are also preferably two in number, each block being adapted for the purpose of attachment of one of the rails. The concrete portion in the preferred embodiment of the invention is in a single 45 piece, forming the major part of the tie and supporting the blocks. In one embodiment of my invention, however, which I will describe, the concrete is in a plurality of pieces.

50 Referring particularly to Figs. 1 to 4 inclusive, the blocks 2, 2 are preferably made of wood, and of rectangular cross-section. The ends have beveled corners 3, as shown. In the preferred embodiment of the invention, the tie is uniformly of rectangular 55 cross-section throughout its length, the ends

being formed of the blocks and concrete portion, while the center part is formed of the concrete portion alone, as best illustrated in Fig. 2. This produces a concrete portion, 60 of the full depth of the tie in the middle, but at the ends, where it is under the blocks, it is less than full depth, forming endaway portions. The proportion of depth occupied by the concrete and wood will depend 65 upon the thickness of the latter, but it may be approximately equally divided. Each block is held removably in position on the concrete by the following devices: A cap plate 4 is removably attached to the end of 70 the tie. This cap plate has beveled top and bottom edges 5, the angle of the bevel being the same as that of the corners of the block 2. These cap plates are held in position by rods 6, which preferably extend through- 75 out the entire length of the tie. The ends of the rods are threaded and pass through holes in the cap plate, the threaded ends being for the attachment of nuts 7. I prefer to extend these rods entirely through the 80 tie, but it is apparent that this is not necessary. The inner ends of the blocks are held in position by plates 8 having beveled upper edges which engage with the beveled corners of the inner ends of the blocks. These 85 plates 8, in the preferred embodiment of the invention, are embedded in the concrete, as shown. I prefer to connect the two plates 8, 8 by a bar 9, or other connection. One way of forming the device is to make the 90 two plates and bar of a single metal casting, as shown. The concrete occupies the position between the two plates 8, 8 as shown, and the bar acts as a reinforcement for the concrete. It is apparent that, by re- 95 moving the nuts 7, one or both of the cap plates may be entirely removed or partially moved outward a sufficient distance to permit the removal of one or both of the blocks 2, 2. The blocks can then be turned to 100 bring their lower face uppermost or taken off and be replaced by others without lifting the tie. I prefer in practice to use a plurality of rods 6, such as the two illustrated. By making the blocks with the top 105 and bottom edges beveled, as shown, they may be reversed. The bevels of the blocks, acted upon by the beveled edges on the plates 4 and 8 produce a wedging effect, when the nuts are screwed up, and hold the blocks 110 firmly and immovably in position.

In order to increase the strength of the

tie in the middle—as the weight on the rails at the ends of the tie have a tendency to buckle it upward—I prefer to use a reinforcement 10, in the form of an anchor with an enlarged head, as shown. I have shown a single reinforcement connected to the two rods 6, 6, but it is apparent that such specific form of reinforcement need not be employed. The reinforcement has openings, as shown in Fig. 4, through which the rods pass.

Fig. 5 illustrates a mold by means of which my preferred embodiment of the invention may be constructed, the mold being indicated at 11. This mold has slots 12, 12, in the ends, for the removal of the rods 6, 6. In molding the tie, blocks 13, which may be the same size as the blocks 2, 2, or larger, to allow for shrinkage of concrete, are introduced in the bottom of the mold, the cap plates and end plates with their connecting rods are then introduced in proper position and the reinforcement 10, as shown, is put in place and supported upon the rods. If desirable, the blocks 2, 2, which are to be ultimately employed with the tie, may be within the mold. The concrete material is then introduced in place between the blocks and above the same, and when it is sufficiently set, the tie may be removed from the mold by turning the latter upside down. It is apparent that it is not necessary to cast the tie with the cap plates in position, although when they are cast in position they may be sure of a proper fit on the concrete.

I prefer to locate the rods 6, 6 in the center line of the tie, and in the embodiment of the invention described, they are embedded in the concrete. They may, however, be partly embedded in the concrete and partly in the block, as shown in Fig. 8, thus making connection between the rods and the cap plates nearer to the blocks, and increasing the strength of the structure.

In Figs. 6 and 7 I have shown an embodiment of my invention wherein the tie is composed of two composite portions held in proper relation to each other by the tie rods 6, 6 alone. In this embodiment of my invention the concrete is in the form of blocks corresponding in size with and located below the wooden blocks 2, 2. The outer ends of the concrete and wooden blocks are secured together by means of the cap plates 4, 4, and their inner ends are supported by plates, 8, 8, which are identical with the plates 8, 8, except that they are deeper, and inclose the ends of the concrete portions as well. The rods 6, 6 are provided with shoulders 14, 14, against which the plates 8, 8 rest, whereby when the nuts 7, 7 are in place the two rail supporting parts of the tie are

firmly and rigidly held in their proper relative positions.

In all of the embodiments of my invention, the rails are secured to the blocks by means of the usual fastenings. In lieu of the nuts 7, on the rod 6, I may use any other kind of fastenings, as are well known.

I have described and illustrated the angle 70 of bevel on the wooden blocks and on the cap and the end plates as the same, but it is apparent that they may be different, provided that the blocks will be firmly and rigidly held in position.

In accordance with the provisions of the patent statutes, I have described the principle of my invention, together with the apparatus which I now consider to represent the best embodiment thereof; but I desire 80 to have it understood that the apparatus shown is merely illustrative and that the invention can be carried out in other ways.

Having now described my invention, what I claim as new and desire to secure by Letters Patent, is:—

1. A railroad tie comprising a bottom and central portion of concrete, wooden blocks at the top adjacent the ends of the tie, plates covering the ends of the concrete portion and the outer ends of the wooden blocks and rods passing through the tie and holding said plates against the ends thereof.

2. A railroad tie comprising a bottom portion of concrete, an upper central portion of concrete having a re-inforcement therethrough, and plates at the ends thereof, wooden blocks on each side of said upper central portion extending outwardly even with the ends of the concrete bottom portion, plates covering the ends of the tie, and rods passing through the tie and the plates on the ends thereof.

3. A railroad tie formed of concrete and a block, said block being of parallelepipedon 105 shape with two opposite corners at each end beveled, and a plate with a beveled portion engaging with each end of the block, and means for forcing the plates into contact with the block.

4. A railroad tie formed of concrete and a block, said block having beveled ends, a plate with a beveled portion engaging each end of the block, and a rod passing through one of the plates and a fastening means for 115 the rod to force the plate into contact with the block.

This specification signed and witnessed this 27th day of January, 1911.

WILLIAM JAMES MORTON.
